UNITED STATES PATENT OFFICE.

JOHN F. GEIBEL, OF BUFFALO, NEW YORK, ASSIGNOR TO KAUSTINE COMPANY, INC., OF BUFFALO, NEW YORK.

TOILET.

Application filed April 26, 1920. Serial No. 376,506.

To all whom it may concern:

Be it known that I, JOHN F. GEIBEL, a citizen of the United States, residing at Buffalo, in the county of Erie and State 5 of New York, have invented a new and useful Improvement in Toilets, of which the following is a specification.

This invention relates to toilets or closets of the kind in which no water is used for 10 flushing the toilet bowl and in which the sewage passes through a large vertical tube or passage into a tank or reservoir in which it is preferably sterilized and disintegrated.

The objects of this invention are to produce 15 a device of this kind which is so constructed as to greatly facilitate the work of installing the toilets; also to provide means of improved construction for agitating the sewage; also to improve the construction of devices of this kind in other respects hereinafter specified.

In the accompanying drawings:

Fig. 1 is a transverse sectional elevation 25 of a toilet embodying the invention.

Fig. 2 is a fragmentary front elevation thereof.

Fig. 3 is a fragmentary transverse sectional elevation thereof showing a different arrangement of the parts.

Fig. 4 is a fragmentary longitudinal sectional elevation thereof.

Fig. 5 is a fragmentary elevation on an enlarged scale of the adjustable connecting rod.

Fig. 6 is a fragmentary sectional elevation thereof on line 6—6 Fig. 5.

Fig. 7 is a fragmentary section of the drop tube on line 7—7 Fig. 2.

A represents a toilet bowl or closet which 40 may be of any suitable or desired construction and which is mounted on the floor α of a building. This bowl is connected by a substantially vertical drop tube or passage with a tank B arranged under the floor α and which contains a chemical solution which disintegrates and disinfects the sewage. This tank contains the usual stirring or agitating devices by means of which the sewage is mixed with the chemical solution and disintegrated, the agitating devices being actuated by means of a rod or other means extending from the tank through the floor into proximity to the closet bowl. All of these parts have heretofore been used in connection with toilets of this kind and

of themselves constitute no part of this invention.

Toilets of this kind cannot be completely assembled at the factory and arrangement of the toilet bowl relatively to the tank 80 may vary considerably in different installations. It is therefore desirable to make the toilets of such construction that the parts thereof are adjustable relatively to each other without necessitating any machine 85 work or cutting of parts after the same have left the factory. For that reason the toilet is provided with some features which I will now describe.

The tank B is preferably located somewhat below the ground and consequently the distance of the toilet bowl A above the tank depends upon the distance of the floor α above the ground or above the tank. Consequently means are preferably provided for 70 varying the length of the drop tube and of the connecting rod for actuating the agitator. For this purpose the connecting rod is made in two sections C and D, the lower section D being secured to a crank e 80 of the agitator shaft E. The two sections are preferably substantially channel shaped and arranged one within the other and both sections are provided with a plurality of holes which are adapted to be placed into registration and one or more pins or bolts d' , passing through the holes, serve to connect the two sections. In this manner the length of the connecting rod may be varied 85 to suit different installations without necessitating cutting or other machine work in installing the toilet, and the channel shaped cross section produces a strong and rigid connecting rod and holds the two parts 90 thereof in correct relations to each other. The agitating device includes the usual blades or paddles e' secured to the shaft E which stir or disintegrate the contents of the tank B when the shaft E is rotated or oscillated. The shaft is suitably journaled in 95 the tank B in any desired manner, one end of the shaft being journaled in a bearing e^2 secured to an end wall of the tank and the other end being journaled in an arm or bracket e^3 extending inwardly from the 100 cylindrical wall of the tank.

The upper section of the connecting rod is pivotally connected with an operating rod F, which is movable vertically and which transmits motion to the connecting 110

rod. This rod in the construction shown is slidably arranged on the toilet bowl, the upper portion of the rod extending through a hole in the rear of the seat portion of the toilet bowl. The toilet bowl is also provided with an eye or guide member f through which the guide rod passes and which together with the hole in the toilet seat forms a guide for the actuating rod. By means of this construction no separate guide means or support for the actuating rod is required and the correct alignment of the actuating rod is assured. Consequently in installing the apparatus, the skill or accuracy of the workmen is not depended upon to properly align the operating rod with the adjusting mechanism, thus ensuring at all times the proper operation of the agitating mechanism after the toilet is installed.

It is desirable to yieldingly hold the crank s as much as possible out of alignment with the drop tube so that sewage dropping into the tank will not fall upon the crank. For this purpose the agitator mechanism is provided with a counterweight G , which may be secured on either one of two arms g g' which are rigidly secured on the shaft E . The weight G is designed to counteract the weight of the connecting rod, crank and operating rod when the weight is substantially in the position shown in Figs. 1 and 3, and when in this position will hold the crank out of the path of sewage dropping into the tank. The counterweight has the further object of tending to cause the shaft E to make a complete revolution owing to the momentum which the weight acquires when the operating rod is depressed. By varying the counterweight supporting arms g and g' substantially at 45° from the horizontal, the relation between the counterweight and the weight of the crank, connecting rod and operating rod is such that the counterweight will always return the crank substantially to the positions shown in Figs. 1, 3 and 4.

It will be seen that the toilet bowl can be so installed that the front of the bowl may face toward either side of the tank and that consequently the connecting rod may enter the tank from either side of the drop tube. By providing the two counterweight arms g g' , the toilet bowl may easily be placed to face in either direction since if it is desired to reverse the bowl from the position shown in Fig. 1, it is only necessary to turn the shaft E through one half of a revolution and place the counterweight G on the arm g' , as shown in Fig. 3. The connecting rod will then be arranged on the other side of the drop tube.

The drop tube shown includes two sections telescopically arranged so that the toilet bowl may be arranged at different distances above the tank without necessitating

special fitting of the parts of the drop tube. In order to make a substantially air and liquid tight joint at the connection between the two parts of the drop tube, one of the telescoping sections is preferably provided with a ring or band H secured thereto and forming a sliding connection with the other section. In the construction shown, this ring is secured to the outer tube h of the drop tube near the upper edge thereof and has a sliding connection with the inner section h' . This ring forms the bottom of an annular groove or recess between the two sections of the drop tube, which recess in the construction shown is filled with cement of any suitable kind thus forming a tight seal between the parts of the drop tube. Any other means for sealing the joint between the parts of the drop tube may be employed.

The agitator described may be actuated either by pulling up or pushing down the operating rod, thereby either causing the agitator shaft to make one or more complete revolutions or to oscillate, depending upon the force applied to the operating rod. The toilet can be easily installed and requires no skilled labor nor the use of cutting tools to make an installation, and the parts thereof are so constructed that the proper alignment and correct operation of the movable parts of the device is assured.

I claim as my invention:

1. In a toilet, the combination of a tank, a toilet bowl arranged above said tank, a drop tube connecting said tank and said toilet bowl and comprising two sections which are arranged to permit said bowl to be turned to different positions with respect to said tank, an agitator in said tank, an actuating rod connected to said agitator and having a portion arranged adjacent to said bowl, and means on said agitator for normally holding said agitator in different positions, depending on the position of said bowl relatively to said tank.

2. In a toilet, the combination of a tank, a toilet bowl arranged above said tank, a drop tube connecting said tank and said toilet bowl and comprising two sections which are arranged to permit said bowl to be turned to different positions with respect to said tank, an agitator in said tank, an actuating rod connected to said agitator and having a portion arranged adjacent to said bowl, and a counterweight adapted to be arranged in different positions on said agitator to hold said agitator in correct relation to said bowl.

3. In a toilet, the combination of a tank, agitator mechanism arranged in said tank and including a shaft extending substantially centrally in said tank, a toilet bowl arranged above the central portion of said tank, a crank portion on said shaft arranged

- underneath said bowl, a connecting rod secured to said crank portion and extending into proximity to said bowl, and a counterweight on said shaft arranged to normally move said crank into a position out of the path of movement of the sewage from said bowl into said tank.
4. In a toilet, the combination of a tank, agitator mechanism arranged in said tank, 10 said agitator mechanism including a shaft having a crank and a counterweight connected with said shaft, said counterweight being so arranged as to hold said crank normally out of the path of movement of sewage into said tank.
5. The combination of a tank adapted to receive sewage, a drop tube terminating in the upper part of said tank and through which sewage enters said tank, an agitator 20 mechanism arranged in said tank and including a shaft, said shaft having a crank which is adapted to extend around the path of movement of the sewage from the drop tube into the tank, a connecting rod secured 25 to said crank, and a counterweight on said shaft which facilitates the rotation of said shaft by said connecting rod and also balances the weight of the connecting rod so as to hold said crank out of the path of movement of sewage into said tank.
6. The combination of a tank adapted to receive sewage and having an opening through which sewage is introduced into said tank, an agitator mechanism arranged 35 in said tank and including a shaft, a crank on said shaft which is adapted to extend around the path of movement of the sewage into said tank, a pair of arms on said shaft extending at an angle to each other, a 40 counterweight adapted to be secured to either of said arms to normally hold said shaft in a position in which said crank extends to either side of the path of movement of the sewage.
- 45 7. The combination of a tank adapted to receive sewage, a toilet bowl adapted to face in either of two opposite directions with reference to said tank, agitator mechanism in said tank including a shaft, a crank on 50 said shaft, actuating means for turning said shaft which are connected at one end to said crank and the other end of which is arranged in operative relation to said bowl, a counterweight adapted to be secured in different positions on said shaft to hold said crank on either side of the path of movement of the sewage into said tank, the positions of said counterweight depending upon the direction in which said bowl faces.
8. In a toilet, the combination of tank, 60 rotary agitator mechanism arranged in said tank for operating upon sewage deposited therein, means for maintaining said agitator mechanism in a normal inoperative position, manually actuated means for rotating said agitator to agitate sewage in said tank, said first-named means acting to return said agitator mechanism to inoperative position when the actuated means are released.
9. In a toilet, the combination of a tank 70 adapted to hold sewage, oscillatory agitator mechanism arranged in said tank for agitating the sewage therein and including a substantially centrally arranged shaft, agitator blades on said shaft, a counterweight 75 arranged on an arm secured on said shaft for maintaining said mechanism in a normal inoperative position, and means for moving said agitator mechanism from said inoperative position against the action of 80 said counterweight for agitating material in said tank.
10. In a toilet, the combination of a tank, 85 a toilet seat, an agitator mechanism arranged in said tank and including a shaft having a crank portion, a connecting rod secured to said crank portion and extending into proximity to said seat, said connecting rod including two parts adjustably connected to vary the length of said rod, and a counterweight secured on said shaft and adapted to counteract the weight of said rod and to hold said crank and rod in a position out of the path of movement of sewage into said tank.

Witness my hand this 21st day of April, 1920.
